US00D862834S

(12) **United States Design Patent** (10) Patent No.: **US D862,834 S**
(45) Date of Patent: **** Oct. 15, 2019**

(54) **CRACKER**

(71) Applicant: **Mondelez Europe GmbH**, Glattpark
(CH)

(72) Inventors: **Karine Coue Briant**, East Hanover, NJ
(US); **Vani Vemulapalli**, East Hanover,
NJ (US)

(73) Assignee: **Mondelez Europe GmbH**, Glattpark
(CH)

(**) Term: **15 Years**

(21) Appl. No.: **29/569,423**

(22) Filed: **Jun. 27, 2016**

(51) LOC (12) Cl. **01-01**
